ESCUTCHEON FOR A DOOR LOCK

Van Day Truex, New York, N. Y., assignor to The Yale & Towne Manufacturing Company, Stamford, Conn., a corporation of Connecticut

Application May 4, 1956, Serial No. 41,342

Term of patent 7 years

(Cl. D50—6)

Fig. 1.

Fig. 2.

Fig. 1 is a front elevational view of an escutcheon for a door lock showing my new design. Fig. 2 is a longitudinal section taken on the line 2—2 in Fig. 1.

I claim:

The ornamental design for an escutcheon for a door lock, substantially as shown.
